GREASE RETAINER PULLER AND THE LIKE

Earl A. McKee and Joseph A. Schachtell,
Chicago, Ill.

Application March 18, 1940, Serial No. 324,492

2 Claims. (Cl. 29—88.2)

This invention relates to a puller and more particularly to a grease retainer ring puller, although it may be employed with equal advantage for other purposes.

It contemplates more especially the provision of an improved puller that can be remotely controlled to expand members thereon for insertion behind an internally located body to effect the convenient removal thereof.

The need for pulling instrumentalities is predominantly present in the removal of an internal member or members comprising part of an assembly unit. This is particularly true in removing grease retainer rings that are remotely confined within shaft housings where access is difficult and removal of such parts ordinarily entails a great deal of time, labor and expense.

One object of the present invention is to simplify the construction and improve the operation of devices of the character mentioned.

Another object is to provide an improved puller that is extensible within narrow constrictions for positioning behind elements to be pulled or removed and can be expanded by an arm actuator.

Still another object is to provide a simple and inexpensive expandable element engaging member in conjunction with a moment arm for enabling the effective and convenient removal of parts.

A further object is to provide pivotally associated members that cooperate with each other to fulcrum one relative to the other for effectively pulling parts that are not readily accessible.

A still further object is to provide interconnected levers to serve as a fulcrum for effectively pulling parts engageable by an expandible member provided thereon.

Still a further object is to provide an expandible part engaging member mounted on an arm for insertion in ordinarily inaccessible positions with a remotely operable actuator to render such expandible behind the inaccessible part to be removed therewith.

Other objects and advantages will appear from the following description of an illustrative embodiment of the present invention.

In the drawing:

Figure 1 is a perspective view of a puller embodying features of the present invention, it being shown applied to a grease retainer assembly shown in dotted outline.

Figure 2 is a fragmentary sectional view in elevation taken substantially along line II—II of Figure 1.

Figure 3 is a perspective view of a part engaging jaw member shown in assembled position in Figure 1.

Figure 4 is a fragmentary sectional view taken substantially along line IV—IV of Figure 1.

Figure 5 is an edge view in elevation of the device shown in Figure 1.

Figure 6 is a sectional view taken substantially along line VI—VI of Figure 1.

10 The structure selected for illustration comprises an elongated bar stamped, forged or otherwise shaped from rectangular sheet material to define an elongated handle 10. The handle member 10 has an offset extremity 11 that is disposed laterally of the plane of the handle 10 to serve as a fulcrum mount for a jaw 12. The jaw 12 is cast, forged or otherwise shaped from a metallic bar to present furcated extremities 13—14 that are provided with aligned bores 15 to receive a pin 16 therethrough with the handle member offset 11 disposed therebetween for pivotal connection therewith.

It will be observed that the jaw 12 has its free engaging end serrated as at 17 to engage a rim or end surface 18 which, in this instance, constitutes an upwardly mounted flange of an axle housing 19. The furcations 13—14 on the jaw 12 are defined by an intermediate slot 20 that freely receives the offset handle member 11 to permit pivotal movement relative thereto before engaging the handle member extremity edge 21 serving as a stop therefor. In order to enable the convenient expansion of the handle member 10 from a suitable anchoring expedient such as a nail or the like mounted on the wall or bench, an aperture 22 is provided in the free extremity 23 thereof.

In order that the handle member 10 may serve as a fulcrum for other instrumentalities, it is provided with a longitudinal slot 24 proximate to the offset extremity 11 thereon to present spaced bores 25, 26 and 27, in this instance three, which communicate with the elongated slot 24 (Figures 1 and 2) to receive a flat stud 28 therethrough. The flat stud 28 has a diameter that substantially corresponds with the bores 25, 26 and 27 for retention therein against displacement; however, diametrically disposed flat sides 29 and 30 are provided on the stud 28 to correspond with the width of the elongated slot 24 for displacement therealong when the stud 28 is rotated so that its sides 29—30 are in registry with the elongated slot 24.

When the flat sides 29—30 are out of registry 55 with the slots 24, the intermediate aligned por-

tions of the stud 28 register with one or the other of the bores 25, 26, or 27 depending upon the position thereof in the elongated slot 24. Consequently, the stud 28 will serve as a pivotal housing adjustable along the length of the elongated slot 24 in predetermined positions depending upon the number and location of the bores 25, 26 and 27. As shown, the stud 30 has an enlarged head 31 on one end thereof to abut against one side of the handle member 10 while extending through the elongated slot 24 while registering with one of the series of apertures 32, in this instance six, provided along the longitudinal median line of a lever 33.

A threaded nut 34 engages the stud 28 to retain the elongated lever 33 on the stud 28 serving as a pivotal mount therefor. The elongated lever 33 is disposed at an angle or normal to the housing member 10 to present a free extremity 35 which is adapted to enter a restricted opening or inaccessible interior of any member such as an axle housing 19 (Figure 1). A lever extension 36 beyond the other edge of the handle member 10, serves as a manual grip to position and control the pivotal direction of the lever extremity 35. The extent of projection of the lever extremity 35 is determined by the expansion of the pin 28 through one of the series of apertures 32 and to this end the threaded nut 34 is removable from the pin 28 to permit this adjustment along the lever 33, the latter being laterally adjustable along the handle grip member 10 within the limits of the elongated slot 24 to enable the axial positioning thereof within a chamber such as the axle housing 19 so that the jaw 12 will be engageable with its periphery such as the flange 18.

Because of the offset 11 provided on the handle member 10, it will be apparent that the engaging jaw 12 serves as a fulcrum in the plane of the lever 36 that is pivotally attached to the handle member 10 beyond the offset extremity 11 thereof to compensate for the thickness of the lever 36 that is disposed adjacent to the flat side of the handle member 10. In order to enable the removal of normally inaccessible parts such as grease retainer rings 37 from the interiors of devices such as, in this instance, an axle housing 19, a pair of gripping members 38 and 39, in this instance two, are pivotally mounted to the extremity 35 of the lever 33.

To this end, the gripping members 38-39 are of substantially U-shaped cross-section so that they confront each other to receive the lever bar 36 therebetween for full collapsible association therewith. Pivotal mounting pins 40 and 41 extend through apertures 42 provided in the U-shaped grippers 38-39 and project through corresponding apertures provided in the lever bar extremity 35 so that the grippers 38-39 can pivot relative thereto from an extreme collapsed position (shown in full lines in Figure 1) to an angular expandable position (shown in dotted outline in Figure 1).

The grippers 38-39 are rendered expandable and held in any adjusted expanded position by means of a plate 43 provided with a spear-head 44 at one extremity thereof to enter between the grippers 38-39 and effect their spreading displacement about their pins 40-41. To this end, an expandable actuator plate 43 is provided with lateral flanges 45 and 46 that are bent to conform with the shape of the lever bar 33 to define an embracing closure 47 thereon. The embracing closure 47 serves as a body guide for the spear-

head 44 that is freely slidable and displaceable along the length of the lever bar 33.

To enable the displacement of the spear head guide body 47 along the lever bar 33 and to enable the actuator thereof from a remote distance, one of the spear head body flanges 45 extends rearwardly to present an elongated strap 48 disposed along one edge of the lever bar 33 to terminate in an offset lip 49 which can be manipulated with the attendant's finger to displace the spear head 44 bored away from the complementary grippers 38-39. It will be observed, therefore, that the grippers 38-39 can be expanded from a remote point proximate to the pivotal stud 28 that serves as a connection between the handle member 10 and lever bar 33 and thus will be freely expandable even after the extremity 35 of the lever bar 33 has been inserted for an appreciable distance within the interior of a member such as the axle housing 19.

So that the grippers 38-39 will be expandable for the maximum extend within the confines such as a cylindrical interior wall 50 of a wheel housing 19, the extremities of the grippers 38-39 are cut on the bias as at 51 for alignment with the interior wall 50 of any member 19 after the grippers 38-39 have been expanded to their maximum distance to effect contact therewith. This is usually accomplished after the lever bar extremity 35 together with its collapsed grippers 38-39 have been inserted beyond a part such as the grease retainer ring 37 to be removed from the interior of the member 19.

Thereupon, the lip 49 is grasped by the attendant's finger to displace the spear 40 with its body 43-47 along the lever bar 33 to actuate and separate grippers 38-39 for retention in any expanded position. With this accomplished in the manner illustrated in dotted outline in Figure 1, the attendant can hold the lever bar handle extension 36 while displacing the handle member 10 in a clockwise direction with the other hand (viewed from Figure 1) so that the fulcrum jaw 12 will engage the rim or flange 18 of the tubular member 19 and thus displace the lever bar 33 outwardly with the part to be removed such as the grease retainer ring 37.

It will be apparent, therefore, that the part to be removed such as the retainer 37 is engaged from behind by the grippers 38-39 and forwardly removed in a direction commensurate with the displacement of the lever bar 33. The lever bar 33 is readily displaced on the comparatively large movement arm that is presented between the fulcrum jaw 12 and the handle member extremity 10 relatively to the interconnecting pin 28 that retains the handle member 10 and lever 33 in pivotal assembled position. So that the part to be removed such as the grease retainer ring 37, will not be mutilated to the extent that it will interfere with the withdrawal thereof, the grippers 38-39 are presented with rounded engaging extremities 52 that merges from the inclined sides 51.

With this arrangement of parts, a very simple and effective pulling device has been provided that is readily insertable for connection to a normally inaccessible position. The pulling device is simple in construction, dependable in operation, and will serve to free the part to be removed from any internal position to which ordinary tools are not accessible. Various changes may be made in the embodiment of the invention herein specifically described without departing from the invention or sacrificing any of the ad-

vantages or features thereof, and nothing herein shall be construed as limitations of the invention, its concept or structural embodiment as to the whole or any part thereof except as defined in the appended claims.

We claim:

1. In a puller device, the combination with a flat bar member, of grippers pivotally mounted to said flat bar member on opposite sides thereof, each of said grippers having an angular cross section providing at least two side faces overlying two sides of said bar, one side face of each of said grippers overlying the same side of said bar and providing opposed edges at that side of said bar in their collapsed position, slidable means on said flat bar member having a surface adapted to wedge between said opposed edges to spread said grippers from their collapsed position, handle means pivotally connected to said flat bar member for affecting the displacement thereof relative to another member, and an engaging element on said pivotally connected displacing handle means for more effectively operating said gripper mounted flat bar member and said grippers.

2. In a puller device, the combination with an

elongated flat bar member, of substantially U-shaped grippers pivotally mounted to said elongated flat bar member for edge reception thereon to present confronting surfaces overlying said flat bar member and embracing the same in their collapsed position adjacent portions of said V-shaped grippers lying on the same side of said bar and presenting opposed edges, slidable means having a pointed extremity extending from a flat portion overlying said elongated flat bar member in the path of said opposed edges for operation thereon to spread said grippers from their collapsed position, handle means slidably and pivotally connected to said elongated flat bar member for affecting the displacement thereof relative to another member, and an engaging element on said pivotally connected displacing means for more effectively withdrawing said gripper mounted member, said flat bar member having a series of openings therein to receive said pivotally connected handle means therein for adjustment of the engaging element relative to the work.
